UNITED STATES PATENT OFFICE.

JOSEPH W. SHARP, OF PHILADELPHIA, PENNSYLVANIA.

GAS BURNER.

Application filed September 13, 1921. Serial No. 500,322.

To all whom it may concern:

Be it known that I, JOSEPH W. SHARP, a citizen of the United States, residing at Philadelphia, in the county of Philadelphia and State of Pennsylvania, have invented 5 certain new and useful Improvements in Gas Burners, of which the following is a specification.

This invention relates to gas burner attachments for coal burning stoves and furnaces and is an improvement on my pending application filed April 11, 1921, and Serial No. 460221, and the primary objects of the present invention are first, to provide a 10 novelly constructed heat distributing hood or muffler; second, to provide a novel support for the heat distributing hood or muffler and burner which will permit adjustment of the hood and burner in relation to each other and to the stove or furnace with which it is associated; third, a novel burner and means for arranging the burner in the hood or muffler; and, fourth, a novel burner cap for the burner.

With these and other objects in view, the invention consists in the novel construction, arrangement and formation of parts, as will be hereinafter more specifically described, claimed and illustrated in the accompanying drawings, forming a part of this specification, in which drawing:

Figure 1 is a perspective view of a coal burning cooking stove partly in section, showing the improved gas burner attachment associated therewith.

Figure 2 is a sectional view through the stove illustrating the means of associating the novel burner attachment therewith, parts of the burner attachment being shown 40 in section.

Figure 3 is a transverse section through the stove taken on the line 3—3 of Figure 2.

Figure 4 is an enlarged sectional view through one of the burner tubes and caps.

Figure 5 is an enlarged bottom plan view of one of the burner caps.

Figure 6 is a plan view of the top of one of the burner tubes.

Figure 7 is a plan view on a small scale of a modified form of burner hood or muffler.

Figures 8, 9 and 10 are plan views of further modified forms of the burner hoods or mufflers, which are adapted to be used

with various styles and shapes of stoves and furnaces.

Referring to the drawings in detail, wherein similar reference characters designate corresponding parts throughout the several views, the letter A indicates a coal 60 burning cook stove; and B the novel burner attachment which is adapted to be associated therewith.

While in the drawings the attachment has been shown in connection with a cook 65 stove, it is to be readily understood that the attachment is adapted to be used with any preferred type of coal burning stove or furnace, and that the attachment can be modified to accord with the construction 70 thereof as shown in Figure 7 to 10 inclusive.

The stove A may be of the usual or any desired construction and includes the base 15, the fire box 16 which can be provided 75 with the usual fire brick lining 17 and the ash pit 18. The top 19 of the stove is arranged in the usual manner and it is preferred, that the mufflers or heat distributing hoods be arranged below the burner openings thereof. This is of course not necessary, as the heat thrown out therefrom is well distributed throughout the entire area of the fire box.

The ash pit 18 is provided with the usual 85 bottom wall 20 and the front door opening 21 through which the ashes are usually removed. In order to arrange the improved burner attachment B within the stove A, the usual grate and grate bars are removed 90 therefrom as is clearly apparent by referring to Figures 1 to 3 inclusive.

The improved burner attachment B comprises a plate 25, which is preferably formed of fire brick or some other suitable 95 refractory material.

This plate 25, as shown, is substantially rectangular shaped in plan and is adapted to snugly engage the lower surface of the fire box 16, and is disposed below the fire 100 brick 17 in the fire box. The provision of this plate prevents the seeping of cold air into the fire box from the ash pit.

This plate 25 supports the heat distributing hoods or mufflers C and is supported 105 by the novelly arranged supporting member D.

The heat distributing burner hoods C are

also formed of fire brick, clay or some other refractory material. As shown in Figures 1 to 3 inclusive, the same are constructed substantially rectangular shaped in plan and include the side walls 30, the end walls 31 and the top wall 32. The lower edges of the side and end walls 30 and 31 rest upon the plate 25. It can be seen that the lower end of the heat distributing hoods or mufflers are left open. The side walls 30, the end walls 31 and the top walls 32 are provided with relatively small perforations 33, through which the heat and flame is adapted to be projected.

15 There may be any number of the heat distributing hoods or mufflers as may be desired, and according to the size of the stove or fire box. As shown in Figures 1 to 3 inclusive, there are two of the heat distributing hoods or mufflers arranged on the plate 25. In case the stove or furnace is of a relatively large size, the plate 25 can be readily made in sections, if so desired, in order to facilitate the handling and the placing thereof 25 within the stove.

The novel support D for the plate 25 comprises end brackets 35. These end brackets 35 are constructed identically the same, and each includes the U-shaped base portion 36, having the depending legs 37 formed thereon. These legs 37 are provided with outwardly extending feet 38, which receive the adjustable set screws 39. These set screws 39 serve as means for raising and 30 lowering the U-shaped portion 36 as is readily apparent. These set screws 39 engage the lower wall 20 of the ash pit. The side portions of the U-shaped base portion 36 slidably receive arms 40. These arms 35 40 carry adjusting bolts 41 which are slidably mounted in slots 42 formed in the side portions of the U-shaped portions 36. This permits the arms 40 to be readily raised and lowered and held in any desired position in 45 order to support the plate 25 at the desired height in the stove. The upper end of the arms 40, if so desired, may be provided with outwardly extending feet 44, which may be connected by suitable strips 45. These 50 strips 45 extend longitudinally of the plate 25 and form means for supporting the same throughout its entire length. In some instances where the plate is formed relatively small, the strips 45 may be dispensed with.

55 The supporting stand D also supports the burners proper E which will now be described. As shown, there are two burners E, each including a tube 50 which is extended through a suitable opening 51 formed in the plate 25. Each of the burner tubes 50 is adapted to project into the heat distributing hoods or mufflers C and have their lower ends flared as at 52, so as to permit the entrance of air into the same. The 60 lower flared ends 52 of the burner tubes are

provided with lower walls 53, which can be provided with suitable air inlet openings 54 and a suitable cap 55 is carried by each wall so as to control the size of the openings in the lower walls 53 and thus control the flow of air through the same. The burner tubes 50 are fed from a longitudinally extending main supply gas pipe 56, which is provided with upstanding nipples 57. These nipples 57 are extended into the lower flared ends 52 of the burner tubes 50 and can be threadably connected thereto if so desired. Suitable gas cocks 58 are disposed within the burner tubes and are provided with crank handles 59, which can be connected to a single operating rod 60. As shown this operating rod 60 has its outer end extending through the ash pit door opening 21 and is provided with a handle 61. The gas supply pipe 56 rests in seats 62, formed in the bight portions of the U-shaped portion 36 of the brackets 35, and suitable cap members 63 are provided for holding the supply gas tube 56 in position. Each burner tube 50 is provided with a novel burner cap 65, which is preferably formed of clay or other refractory material. Each of the caps 65 has embedded therein a copper or other metallic screen 66, which prevents the falling of foreign matter into the burner tube. In order to provide an efficient means for detachably connecting each burner cap to each burner tube, the burner caps are provided with bayonet slots 67, which are adapted to receive 100 outstanding lugs 68 formed on the upper end of the burner tubes.

From the foregoing, it can be seen that the stand or support D forms an efficient means for not only supporting the plate 25 and the burner proper, but also forms an efficient means for adjusting the position of the plate 25 and the burner caps 65 in the heat radiating hoods or mufflers C.

It can be seen that when it is desired to 110 adjust the position of the plate 25, it is merely necessary to loosen the bolts 41 and then slide the arms 40 upwardly until the plate 25 reaches the desired height. The bolts 41 are then tightened. When it is desired to adjust the burner caps 65 within the heat radiating caps or mufflers C, it is merely necessary to turn the set screws 39. During the adjusting of the set screws 39, the arms 40 can be slid downwardly.

115 It can be seen that the gas will be projected into the mufflers for heat radiating hoods C and the gas is lit from the exterior thereof. The gas is then burned within the hood and will be projected outwardly 125 through the openings 33. The refractory material from which the hoods are constructed will become red hot and effectively distribute the heat throughout the entire top area of the stove.

Thus it can be seen that an efficient means has been provided for effectively cooking or heating which will entirely eliminate the inconveniences associated with wood and coal 5 stoves.

It may be found desirable to seal the edges of the plate 25 to the fire box, in order to render this connection air tight and thereby prevent seeping of cold air into the fire box.

10 If desirable, a pilot 75 may be provided in order to facilitate the lighting of the gas within the hood or mufflers C and as shown the pilot is provided with a T-head 76 which is carried by an upwardly extending gas conducting tube 77, which communicates at its lower end with the gas feed pipe 56. This pilot can be left burning at all times if found desirable.

As heretobefore stated, the mufflers C may 20 be of any desired shape and of any desired number according to the size or configuration of the stove or furnace with which they are associated, and in Figure 7 is shown a substantially circular muffler 80, which is 25 adapted to be arranged centrally on a bed plate 81, of refractory material.

In Figure 8 is shown a series of mufflers 85, 86, and 87, which are formed in the segments of a circle, and these mufflers or heat 30 radiating hoods are disposed upon a common plate of refractory material 88.

In Figure 9 are shown four triangular shaped hoods or mufflers 90, which are disposed with their apex portions inwardly in 35 order to form a figure substantially rectangular in plan, and all of these hoods are disposed upon a common circular plate 91.

In Figure 10 is shown a still further modified form of the invention, in which four rectangular shaped hoods or mufflers 95 are disposed upon a common refractory plate 96. These hoods or mufflers 95 are constructed 40 similar to the muffler C shown in Figures 1 to 3 inclusive, and the same are arranged in pairs upon the plate 96. The forms shown in Figures 7 to 10 are only several of the ways in which the mufflers can be constructed and arranged upon the plate.

Changes in details may be made without 50 departing from the spirit or scope of this invention; but,

I claim:

1. The combination with a coal burning stove including a fire box and an ash pit 55 having a lower wall, of a gas burner attach-

ment therefor including a bed plate of refractory material fitted within the fire box and arranged to snugly engage the walls thereof, a plurality of hoods of refractory material having lower open ends fitted upon 60 said plate, the hoods having a plurality of minute perforations therein, a stand arranged in the ash pit engaging the lower wall thereof, and a gas feed tube extended into the ash pit and supported by the stand, up- 65 standing burner tubes carried by the gas feed tube and extending through the plates and into said hood, valves disposed within the burner tubes, means for controlling said valves, and means for permitting the adjustment of the refractory plate in relation to the ash pit and fire box.

2. The combination with a coal burning stove including a fire box and an ash pit, of a gas burner attachment therefor including 75 a bed plate of refractory material arranged to snugly engage the walls of the fire box, a supporting stand disposed within the ash pit for supporting the plate including a pair of spaced brackets, adjustable arms carried 80 by the brackets for engaging the plate, adjustable legs carried by the brackets for engaging the bottom of the ash pit, hoods of refractory material disposed upon the bed plate, a burner pipe carried by the bracket, 85 upstanding feed tubes carried by the pipe and disposed through the plate, burner caps carried by the tubes and disposed within the hoods, valves for controlling the flow of gas through said tubes, and a pilot burner 90 connected with the gas feed pipe and disposed between the hoods.

3. A gas burner comprising a plate, a hood arranged upon the plate and having one end open, a gas burner tube arranged to 95 project through the plate and into said hood, U-shaped brackets arranged beneath the plate, depending legs on each of said brackets, outwardly extending feet on said legs, adjusting screws engaged with said feet 100 for raising and lowering the brackets, spaced arms extending downwardly from the plate and arranged parallel with the arms of the brackets, the arms of said brackets having slots therein and adjusting bolts carried by 105 the arms on the plate and disposed in said slots whereby to adjust the arms and retain them in an adjusted position.

JOSEPH W. SHARP.
